FREDERIC BARR, OF NEW YORK, N. Y.

ELECTRIC SWITCH

1,107,247.

Specification of Letters Patent. Patented Aug. 18, 1914.

Application filed March 11, 1913. Serial No. 753,568.

To all whom it may concern:

Be it known that I, FREDERIC BARR, a citizen of the United States of America, and residing at New York, in the county of Kings and State of New York, have invented new and useful Improvements in Electric Switches, of which the following is a specification.

My present invention relates more particularly to what are commonly termed rotary snap switches and the general object of the invention is to improve structures of this character by making them more positive in action and by simplifying and reducing the number of parts.

One feature of the invention is an improved form of detent mechanism for controlling the snap action.

Another feature is a special form of mounting for the switch blade which possesses certain important advantages of mechanical strength and thorough insulation.

Another feature is the method of indicating whether the switch is open or closed.

Another feature is an improved form of switch terminal mounting.

Another feature of improvement resides in the bearing for the switch spindle.

The accompanying drawings illustrate the invention in its preferred form and some modifications, but I would have it understood that various other changes and modifications may be made therein without departing from the true spirit and scope of the invention.

Figure 1, is a plan view of a switch embodying my invention and showing the switch "lit" or "on." Fig. 2, is a vertical sectional view. Fig. 3, is a detail perspective view of the handle. Fig. 4, is a drop perspective view of one of the combined circuit and switch terminals. Fig. 5, is a fragmentary perspective view of one method of preventing the circuit terminal from turning. Fig. 6, is a detail sectional view of one form of support for the rotary switch blade. Fig. 7, is a side view of another form of switch blade support. Fig. 8, is a vertical sectional view of a snap switch constructed in accordance with and embodying the invention, with a modified form of indicator. Fig. 9, is a drop perspective of the handle and indicator support of Fig. 8. Fig. 10, is a drop perspective view of the spindle and the various parts which are mounted thereon

below the base. Fig. 11, is a drop perspective of the switch parts which are located on the spindle above the base. Fig. 12, is a horizontal sectional view taken substantially on the plane of the line 12-12 of Fig. 2. Figs. 13 and 14 are similar views of the parts shown in Fig. 12 illustrating the operation of the detent mechanism.

The parts of the switch mechanism may be mounted upon a base 10 of porcelain or other suitable insulating material. This base carries the relatively stationary switch terminals 11. The spindle 12 is rotatably carried by the base and carries the relatively movable contacts or switch blades 13, 13'. The drawing illustrates a switch of the "double pole" type and the base therefore carries two sets of switch terminals while the spindle carries two switch contacts to cooperate with the respective pairs of terminals.

A spring connection is provided between the spindle and the switch blades thereon and to get the necessary snap action a detent mechanism is employed for temporarily restraining the switch blades while storing up the tension necessary to give the snap to the blades. The spring is designated 14 and it is usually held in place by coiling it about the spindle substantially as shown. The upper end of this torsional spring is connected with the spindle as by engaging with a lug 15 on the washer 16 which is fixedly secured upon the spindle, while the lower end of the spring is connected in a suitable way with the support which carries the switch blade or blades. The washer 16 which forms the anchor for the upper end of the spring is preferably engaged upon the spindle by slotting it as indicated at 17 so that it may be slipped edgewise into engagement with an angular portion 18 on the spindle.

The switch blade support is mounted loosely upon the spindle so that the said support and the spindle may be rotated independently of each other. This support embodies certain unique features of construction and consists in substance of a metallic supporting plate 19 which carries on its upper side an insulating washer 19' to which the switch blades are secured. The insulating washer is held against rotation upon the metallic supporting plate by some securing means such as the pins 20 and one of these

- pins may, as shown, be utilized as the anchor for the lower end of the torsional spring, the end of the spring being provided for this purpose with a hook to engage the said pin.
- 5 The switch blades or pole pieces are secured to the insulating washer by rivets 22, or the like fastenings, and the heads of these fastenings are preferably counter-sunk in the under side of the insulating washer substantially as indicated in Fig. 8. To further avoid any possibility of connection between the switch blades and the metallic supporting plate, this plate is preferably recessed or cut away as indicated at 24 at points in line 10 with the fastenings 22. Interference between the two switch blades is prevented in the double pole switch construction by superposing one switch contact above the other, suitable posts 25 being employed for spacing the upper switch blade above the lower. Each of the switch blades is preferably made up of two pieces of spring metal substantially as shown so as to make a yielding frictional engagement with the stationary switch terminals.

The detent mechanism has a cam 26 which is fixedly engaged upon the lower portion of the spindle and which serves to operate a stop member 27 into and out of engagement with certain upstanding holding lugs on a catch plate 28 which is fixedly secured to the base. These lugs, as shown in Figs. 11 to 14, are arranged in pairs spaced so as to receive the stop finger therebetween, the forward one 29 of each pair of lugs constituting the forward stop, and the rearward lug 30 constituting a back stop. It will be noted that the forward or front stop lugs are of less radial distance from the center of the catch plate than the rear stop lugs, the purpose of which will appear later. The preferred manner of forming these upstanding lugs is to strike them up from the metal of which the catch plate is formed. The catch plate is preferably held against turning by providing it with outstanding anchor lugs 31 to engage in corresponding seats in the base. A convenient method of producing these various lugs on the catch plate is to strike up the holding lugs, one at each side or edge of the anchor lugs. This permits of the entire set of lugs being formed at a single operation. To provide a proper bearing for the lower end of the spindle, the catch plate preferably carries a sleeve 33 which may be produced integrally with the plate and a washer 32 seated in a depression in the underside of the base is made with a corresponding sleeve portion 32' which forms a continuation of the bearing sleeve 33.

In order that the stop finger may serve as a stop to limit the forward turning movement of the switch blades, a connection is provided between the support which carries the switch blades and the stop finger. This connection

I have shown in the form of a dependent lug 34 on the under side of the switch blade support which may be made integral with the support and is adapted to make engagement with the rearward edge of the stop finger. In this way it will be seen that the switch blade support has a bearing against the stop finger in the direction of rotation of the spindle.

When the parts are assembled the spring 75 is held under tension so as to produce relative rotation between the spindle and the insulating support for the switch blades and this relative rotation is such as to throw the cam 26 outward so as to project the stop 80 finger into engagement with the lugs on the catch plate.

The normal position of the detent mechanism is illustrated in Fig. 12. Here the spring connection between the spindle and the switch contact support is exerting its tension to turn the spindle counter clockwise. The cam in this position forces the stop finger outward so as to engage it between the front and back stop lugs on the 90 catch plate. The outward movement of the stop finger is limited by the body of the stop finger coming into engagement with the dependent lug 34 on the switch contact support. By thus limiting the outward 95 movement of the stop finger further rotation of the cam and the spindle is prevented and this lug 34 therefore serves to prevent the spindle being turned backward in reference to the switch carrying support. To operate 100 the switch the spindle is rotated to the right by suitable means such as the handle 35 on the upper end of the spindle. This turning movement of the spindle rotates the cam 26 until about in the position shown in Fig. 13, the point of the stop finger is withdrawn from engagement with the front stop lug 29. During this forward turning movement of the spindle, the switch contact support is held against rotation by reason of the lug 110 34 carried thereby being in engagement with the rearward side of the stop finger, and during this period of relative rotation between the spindle and support, the torsional spring is placed under still greater tension 115 so that by the time the finger is withdrawn from engagement with the stop 29, the tension is sufficient to turn the support with a quick snap action. As the spindle is turned far enough to disengage the stop finger from the front stop lug, (see Fig. 13), the cam 26 will occupy such a position that as the stop finger is turned around under pressure of the spring back of the lug 34, the finger will be projected so as to strike the next lug 29 120 which stops it, as shown in Fig. 14. When the handle is released, the spring turns the handle counter clockwise and the cam moves the detent finger out into the space between the lugs 29 and 30. The switch is in this 125 130

way turned step by step with a quick and positive snap action to alternately make and break the circuit at the switch terminals.

To insure a quick and positive release of the stop finger from the front stop lug, the rearward edge of the finger is preferably tapered off as indicated at 27' so as to swing clear of the lug 29 once the point of the finger has been released from the lug. The lugs are inclined so as to insure greater freedom of movement to the detent.

In addition to its function as a means for operating the stop finger, I preferably utilize the cam 26 also as a means for assisting in holding the parts assembled upon the spindle. Thus in Figs. 2 and 8 the switch contact support is shown as movably engaged upon the spindle between the spring anchoring washer 16 at the top and the fixed cam 26 at the bottom. The cam thus serves to limit the downward movement of the contact support upon the spindle and the torsional spring 14 forces the support downward against this cam so that it occupies a definite position upon the spindle and therefore always holds the switch contacts in the plane of the relatively fixed switch terminals. By this construction it is possible to remove the spindle and with it the entire movable portion of the switch mechanism as a unit. Then by disengaging the cam from the spindle, the contact support and other parts may be slipped off the spindle. To facilitate the securing of the cam in fixed position upon the spindle and to permit of its easy removal therefrom, the cam is preferably slotted as indicated at 36 to engage with an annular portion 37 on the spindle. The spindle may be normally secured against disengagement from the base by suitable means such as the slotted securing washer 38 arranged to engage an angular portion 39 on the lower end of the spindle. To positively limit upward movement of the contact support on the spindle an abutment washer 40 may be engaged on the spindle just above said support.

The switch terminals which I have illustrated and which form a part of this invention are of extremely simple and durable construction and each consists of an internally threaded sleeve 45 which carries on its upper end a terminal plate 46, a binding screw 47 being entered in the upper end of the sleeve for clamping the electric conductor and a securing screw 48 being entered in the lower end of the sleeve for fastening the terminal in place. Figs. 2 and 8 illustrate how the terminal is mounted in the base, the base being made with an opening to receive the sleeve and with a shoulder 50 at the lower end of this opening to be engaged by the securing screw 48. The securing screw by its engagement with this shoulder serves to draw the threaded sleeve

downward and thereby clamp the terminal plate in engagement with the top of the base. The terminal plate may be held against rotation by providing it with a lug 51 arranged to engage with a seat 52 provided for that purpose in the base. The terminal plate may be engaged upon the upper end of the threaded sleeve in any suitable way and in the illustration the sleeve is shown shouldered at 53 so that the terminal plate may be fitted down over the same and be riveted or otherwise secured thereto. The condition of the circuit whether "off" or "on," "lit" or "out" is indicated by suitable words or colors on the cover 55 preferably on a recessed or depressed portion 56 to prevent abrasion. A disk 57 carried by the handle and projecting laterally therefrom is provided with a notch or cut-out 58 to disclose only one indication at a time.

In Fig. 6, the plate or support 60 is provided with upstanding lugs 61 embracing the insulating piece 62 which carries the switch blade 13. In Fig. 5, the circuit terminal 63 is let into a recess 64 to prevent rotation. In Fig. 7, the switch blade 13 is riveted to the support 65 but insulated by the bushing 66.

In the form of indicator shown in Figs. 8 and 9 the dial 70 is secured upon the spindle by providing it with a central opening to engage over the end of the spindle and with one or more downwardly struck lugs 72 to engage in recesses or openings 73 in the spring anchoring washer 16. This dial may be additionally secured in place by having the end of the screw bushing 74 to which the handle is attached, engage down over the central portion of the dial substantially as indicated. The dial in this way serves to prevent accidental disengagement of the slotted washer 16 from the spindle because after the dial has been passed over the end of the spindle and the lugs 72 have been interlocked with the seats therefore in the washer, the said washer will be held against edgewise withdrawal from the spindle.

What I claim is:

1. In a rotary snap switch, the combination of a base, switch terminals on the base, a spindle rotatably mounted on the base, a cam fixed on the spindle, a stop finger engaged by the cam and operated thereby, a catch plate secured to the base and provided with lugs upstanding from the surface of the plate and arranged in pairs with the lugs of each pair spaced apart to receive between them the stop finger when said finger is projected by the cam, a support rotatably mounted on the spindle, a dependent lug carried by said support having a bearing against the stop finger in the direction of rotation of the spindle, a switch contact car-

ried by the support arranged for coöperation with the switch terminals on the base, and a connection between the spindle and support exerting tension to turn the spindle rearwardly in respect to the support to thereby normally project the stop finger outward between a pair of the upstanding lugs on the catch plate, whereby when the spindle is turned forwardly the spring will be placed under greater tension and the stop finger will be withdrawn inwardly from between the catch lugs.

2. In a rotary snap switch, the combination of a base, a catch plate secured in the base provided with spaced oppositely disposed lugs cut inward from the edge of the plate and bent upwardly above the plane of the plate to bring the cut edges thereof into position to form front and back stops for a 10 detent finger projected therebetween and with the said front stops extending farther inward toward the center of the plate than the back stops, a spindle journaled at the center of the catch plate, a cam fixed on the lower end of the spindle, a detent finger engaged by said cam and operated thereby, a support rotatably engaged on the spindle and having a bearing against the detent finger in the direction of rotation of the spindle, a switch contact carried by the support, and a spring connection between the spindle and support exerting tension to turn the spindle rearwardly to thereby cause the cam to project the detent finger outwardly 20 in between a pair of the lugs on the catch plate, whereby when the said spindle is rotated forwardly the spring will be placed under greater tension and the detent finger will be withdrawn inwardly from engagement with the forward one of the upstanding lugs between which it was engaged.

3. In a rotary snap switch, a base, switch terminals carried thereby, a spindle rotatably mounted on the base, a catch plate secured to the base provided with upstanding lugs arranged in pairs with the lugs of each pair spaced to form front and back stops for a stop finger projected therebetween and with the front stop lugs disposed nearer the center of the catch plate than the back stop lugs, a cam fixed on the spindle, a stop finger operated by said cam, a support rotatably engaged on the spindle and having a bearing against the stop finger in the direction of rotation of the spindle, a switch contact carried by said support for engagement with the switch terminals on the base, and a spring connection between the spindle and support exerting tension to rotate the spindle to cause the cam to normally project the stop finger outwardly between the stop lugs on the catch plate.

4. In a rotary snap switch, a base provided with seats, switch terminals carried by the base, a catch plate provided with

projecting anchor lugs to engage the seats on the base and with spaced lugs struck up from said plate at opposite sides of each of the said anchor lugs, a spindle journaled on the base, a cam fixed on the spindle, a stop finger operated by said cam, a support rotatably engaged on the spindle, and having a bearing against the stop finger in the direction of rotation of the spindle, a switch contact carried by the support and a spring connection between the spindle and support exerting tension to rotate the spindle to normally project the stop finger outward between the spaced lugs on the catch plate.

5. In a rotary snap switch, a base, a detent plate on the base provided with pairs of lugs upstanding from the surface of the same, the lugs of each pair being spaced apart to provide front and back stops and with the front stops disposed nearer the center of the plate than the back stops, a spindle journaled at the center of the detent plate, a cam on said spindle, a detent provided with a body portion encircling the cam and with a finger extending laterally from the said body portion and adapted to be projected outwardly in between a pair of the front and back stops, a switch blade support rotatably mounted on the spindle, a spring connected between the spindle and the support and exerting tension to rotate the spindle backwardly in respect to the support and a dependent lug on the support bearing against the rearward side of the projecting finger whereby said finger will limit the forward rotative movement of the support, said dependent lug being disposed on the support in position to be engaged by the body portion of the detent whereby by thus limiting outward movement of the detent, to limit backward rotation of the spindle in respect to the support.

6. In a rotary snap switch, a base, switch terminals on the base, a spindle rotatably mounted on the base, a cam fixed on the spindle, a stop finger recessed to receive the cam, a catch plate on the base provided with upstanding front and back stop lugs spaced to receive the stop finger between them, a support rotatably engaged on the spindle above the cam thereon, a switch contact carried by the support for coöperation with the switch terminals on the base, a torsional spring connection between the spindle and the switch blade support exerting tension to rotate the spindle in respect to the support to shift the stop finger outwardly and a dependent lug on the support disposed to be engaged by the stop finger in the outward movement thereof to limit such outward movement and thereby to limit the reverse movement of the spindle in respect to the support.

7. In a rotary switch, a base, a spindle mounted on the base, a contact carrying support mounted on the spindle, a washer pro-

- vided with openings therein and slotted so as to be engaged edgewise over the spindle, a torsional spring connected at one end with said washer and at the other end with the contact carrying support and a dial fitted over the end of the spindle and provided with lugs struck downward therefrom into interlocking engagement with the openings in the slotted washer.
- 10 8. In a rotary switch, a base, a spindle mounted on the base, a switch blade, and a support for the switch blade comprising a metallic plate engaged on the spindle, a washer of insulating material non-rotatively engaged on the plate and fastenings securing the switch blade upon the insulating washer and the metallic plate being recessed in line with such fastenings to avoid contact between said plate and the fastenings.
- 15 9. In a rotary snap switch, a base, switch terminals on the base, a spindle rotatably mounted on the base, a support rotatably engaged on the spindle, a switch contact carried by said support, a cam fixed on the spindle, a torsional spring connection between the spindle and the support, a stop finger operated by the cam, and a catch plate on the base provided with upstanding spaced lugs forming front and back stops to be engaged by the stop finger, the said front stop lugs extending inward nearer the center of the catch plate than the back stop lugs and inclined from their inner extremities toward the edge of the plate to thereby provide clearance for the stop finger when released from the same.
- 20 10. In a rotary switch, a base, a spindle mounted on the base, a switch blade, and a support for the switch blade comprising a metallic plate engaged on the spindle, a washer of insulating material non-rotatively engaged on the plate and fastenings securing the switch blade upon the insulating washer and the metallic plate being recessed in line with such fastenings to avoid contact between said plate and the fastenings.
- 25 11. In a rotary switch, a base, a spindle mounted on the base, a switch blade, and a support for the switch blade comprising a metallic plate engaged on the spindle, a washer of insulating material non-rotatively engaged on the plate and fastenings securing the switch blade upon the insulating washer and the metallic plate being recessed in line with such fastenings to avoid contact between said plate and the fastenings.
- 30 12. In a rotary switch, a base, a spindle mounted on the base, a switch blade, and a support for the switch blade comprising a metallic plate engaged on the spindle, a washer of insulating material non-rotatively engaged on the plate and fastenings securing the switch blade upon the insulating washer and the metallic plate being recessed in line with such fastenings to avoid contact between said plate and the fastenings.
- 35 13. In a rotary switch, a base, a spindle mounted on the base, a switch blade, and a support for the switch blade comprising a metallic plate engaged on the spindle, a washer of insulating material non-rotatively engaged on the plate and fastenings securing the switch blade upon the insulating washer and the metallic plate being recessed in line with such fastenings to avoid contact between said plate and the fastenings.

Correction in Letters Patent No. 1,107,247.

It is hereby certified that in Letters Patent No. 1,107,247, granted August 18, 1914, upon the application of Frederic Barr, of New York, N. Y., for an improvement in "Electric Switches," an error appears in the printed specification requiring correction as follows: Page 2, line 63, for the word "connections" read *connection*; and that the said Letters Patent should be read with this correction therein that the same may conform to the record of the case in the Patent Office.

Signed and sealed this 22nd day of September, A. D., 1914.

[SEAL.]

R. F. WHITEHEAD,

Acting Commissioner of Patents
